K. LIMPERT,
ELECTRIC SIGN,
APPLICATION FILED DEC. 1, 1921.

1,436,270.

Patented Nov. 21, 1922.

UNITED STATES PATENT OFFICE.

KATHERINE LIMPERT, OF NEW YORK, N. Y.

ELECTRIC SIGN.

Application filed December 1, 1921. Serial No. 519,045.

To all whom it may concern:

Be it known that I, KATHERINE LIMPERT, a citizen of the United States, residing at New York, in the county of New York and State of New York, have invented certain new and useful Improvements in Electric Signs, of which the following is a specification.

My invention relates to electric signs and other such illuminated displays. I aim to make the sign most effective in illumination; flexible in design and adaptability to meet varying requirements and conditions of use; easy and inexpensive to manufacture, install, and adjust; and in service convenient and economical as regards both operation and maintenance. Still other advantages obtainable through the invention will appear from my description hereinafter of the best embodiments of the invention known to me.

The invention is applicable with special advantage to the general type of sign represented by United States Patent No. 1,348,816 granted to A. S. Limpert, August 25 3rd, 1920. Another type of apparatus embodying some of the underlying principles of my present application is disclosed in my companion application, Serial No. 519,044 filed December 1, 1921, concurrently here-with.

In the drawings, Fig. 1 is a front view or elevation of an illuminated sign apparatus conveniently embodying my invention.

Fig. 2 is a fragmentary diagrammatic side view of a light source with several reflective devices or units,—about corresponding to a section taken as indicated by the line 2—2 in Fig. 1, but on a larger scale,—illustrating the operation and advantages of my invention.

Fig. 3 is a plan view of one of the reflective illuminating devices or units shown in Figs. 1 and 2, on a larger scale.

Fig. 4 shows a mid-section through such a unit, taken as indicated by the line 4—4 in Fig. 3.

Fig. 5 is a front view of a sign of the "all lamp" type converted into a reflectively illuminated sign in accordance with my invention.

Fig. 6 is a mid-sectional view, similar to Fig. 5, illustrating a reflective illuminating device or unit specially adapted for such conversations as illustrated in Fig. 5.

Fig. 7 is a front view illustrating the ap-

plication of my invention to a sign of the so-called "roof" type.

The sign shown in Figs. 1 and 2 comprises a ground or face plate 11 carrying the desired design,—in the present instance, the letter "H",—in colors visible by day. The electric lamp or lamps 12, 12 here shown as source of light for the sign at night are mounted in suitably located sockets 13 attached to the face plate 11. In Fig. 1, these sockets 13 are centrally situated in the midst of the unilluminated background of the letter, in the upper and lower "cusps" of the H; and the lamps 12, 12 are covered or rendered opaque on their ends by means of caps 14, so as to be themselves practically invisible to an observer. At night, the sign design is luminously set out or outlined by light from the lamps 12, 12 reflected forward from reflective devices or units 15 suitably mounted and arranged on the face plate 11. Since none of the direct rays of the actuating lamps 12, 12 are visible to an observer, each of the devices 15 has almost the exact semblance of an electric lamp; and at some short distance away, it is impossible to tell the difference.

Referring, now, to Figs. 3 and 4 as well as Figs. 1 and 2, it will be seen that the individual reflective device 15 comprises a series or group of somewhat slat-like reflector elements 20 arranged to reflect the obliquely incident light (coming directly from the corresponding lamp 12) approximately perpendicular or normal to the group. As shown, these reflector elements 20 are arranged to extend side by side in the same general direction shutter-wise, in a common general plane in front of but approximating that of the face plate 11 as a whole, at one side of or behind the light source 12. The elements 20 make with their common general plane such common angle that the light of the source 12 directly incident upon them from in front is reflected and thrown forward. Ordinarily, variation in the distance of the reflector unit 15 from the lamp 12 (either in the same or in different signs) will not be so great as to require an adjustable shutter-like mounting of the elements 20, or even the provision of a line of units with the elements 20 set at various different fixed angles. On the contrary, one standard unit, with a group or set of reflector elements 20 fixed at one "universal" angle, will be found

satisfactory under considerable variations in distance of units from the light source.

While the elements 20 might be formed of separate pieces of metal or glass, or stamped out of sheet metal in one piece, or constructed in a great variety of ways, I have found it very simple, convenient, and satisfactory to unite them in one piece of glass, which can readily be pressed into the required multi-prismatic or slat-like form. In the present instance, the united prisms 20 are not arranged with their sloping faces to the rear and one plain, flat surface in front, but just the reverse; this has the advantage of allowing the reflector elements 20 of each unit to be pressed in one solid, integral piece with a rearward projecting base or shank 21 for securing them in position. As shown, this base 21 has bayonet-like projections 22, 22 adapted to be inserted through notches 23 (Fig. 3) at the edge of a circular hole in the face plate 11 and subsequently carried out of registry with said notches by turning of the whole unit 15, so as to "lock" and secure the unit in place. A rubber or other suitable gasket 24 (Fig. 2) interposed and slightly compressed between the unit 15 and the plate 11 prevents turning of the unit by accident or under-vibration,—and the unit is, indeed, so balanced that vibration has little tendency to turn it. As shown, the reflector elements 20 are covered and protected from access of dust, dirt, or other deteriorating agencies by a light-permeable, transparent glass cover 25 cemented, sealed, or otherwise secured in place in an upstanding rabbeted frame or wall 27 (Fig. 4) integral with said reflectors 20. Not only does this cover 25 protect the elements 20 from weather, dust, or dirt, but it is itself much more easily kept clean than they,—both because it presents but a single flat, smooth surface, and because its vertical position minimizes adhesion and accumulation of dust on it. Rain, snow, or sleet have little effect on such a smooth surface.

Whether of reflecting material suitably formed or of non-reflecting material reflectively treated or coated, the elements 20 may be either specular or non-specular reflectors. They may be coated with silver leaf, silver deposit, ordinary mirroring, aluminum leaf or foil, or with other reflecting material. With a consolidated glass unit 15, the reflective material will preferably be applied to the sloping surfaces of the elements 20,—here shown as in front. A dull metallic brightness of the reflector elements 20 (like satin-finished silver) will often suffice to give brilliant illumination: such brightness may be produced by coating a slightly roughened surface with reflective material or by "etching" glass by means of hydrofluoric acid or by appropriate roughening of the mold and then applying mirroring or metallic leaf.

Aluminum paint on metal or glass has also given good results.

Owing to its slight projection from the ground 11 (and also to its transparency), the multi-reflector type of illuminating unit 15 casts practically no shadow on the ground 11; whereas an equivalent single mirror (outstanding some $1\frac{1}{4}$ " to $1\frac{3}{4}$ " from the plate 11) would cast a very long and pronounced shadow. Such shadows fringing a letter in a sign have a very objectionable blurring effect, and often render it illegible at various distances. Moreover, the units 15 lie flat against the face plate 11 and hence present a very neat appearance, and diffuse the light better. The sign is much more readily visible and legible from the side, or at an angle.

The shallowness and shadowlessness of my multi-reflector type of unit not only renders it free from any such objectionable feature as just mentioned, but also obviates all possibility of shading or "blanketing" when one unit 15 is placed directly behind another with reference to their common light source 12. This gives the sign designer untrammeled freedom in the arrangement of units, and enables him to illuminate his sign with a minimum number of relatively large and efficient lamps.

No particular skill is required in the adjustment of the units 15, any more than in their location in the sign: all that is necessary is to turn each unit one way or the other till the position of greatest brilliance (which is that in which the reflector elements lie perpendicularly across the shortest line from the center of the light source there-to) is found. Multicolored, compound-colored, and vari-colored effects can be obtained by using different colored lamps to illuminate different groups of units 15, or the same group at once, or by flashing such lamps in alternation. A variety of color effects can also be obtained by using appropriately colored glass covers 25 for the units 15. The angular range of observation over which the units 15 appear brilliant can be increased by giving the covers 25 the character of lenses rather than of mere flat glass panes of uniform thickness.

Referring, now, to Figs. 5 and 6, it will be seen that if reflector units 15 are made with screw threaded shanks 28 such as shown in Fig. 6 they can readily be substituted for incandescent lamps in existing "all lamp" signs, so as to convert such signs into signs of my type, as in the "E" of Fig. 5. In such a case, some one or two lamps of reasonably high candle power can be used in appropriately located sockets of the sign to illuminate the reflectors in the other sockets,—as, for example, the lamp 12 at the extreme of the mid-stroke of the E in Fig. 5. Such an actuating lamp may form an essential part of the illuminated design, and

hence be provided with a translucent cap designed to reduce its brilliance to a degree indistinguishable from that of the reflector units,—or even left uncapped.

5 As compared with a sign in which each illuminating unit is an incandescent electric lamp, the type of sign shown in Figs. 1, 2 and 5 affords a very considerable economy in both current consumption and lamp renewal costs. According to my invention, for example, both sides of a "Drugs" sign can be well illuminated with ten 25 watt tungsten lamps. The cost of operating such a sign on current at 6¢ per kw. hour is 13¢ per 10 hour; whereas with "all-lamp" letters averaging ten 10-watt lamps apiece for each side, the operating cost would be 6¢ per hour. For operating the two signs five hours each evening for one year, the costs 15 would be \$27.32 and \$109.50, respectively. In each of these signs, lamp replacements must be made something like twice a year, at the same cost per lamp, so that for my type of sign each renewal will cost only one 20 tenth as much as for the other. Since, furthermore, my type employs the larger and longer-lived lamps,—less fragile, especially, under vibration, because their filaments are not so fine,—my type will not require such frequent renewals as to the other 25 type:

The small number of lamps and sockets required for my type of sign makes it quite inexpensive, since the reflector units themselves are not costly, and their insertion in the sign requires little time or skill.

In Fig. 7 is shown a sign (letter "H") of the so-called "roof" type constructed according to my invention. In this sign, the lamps 40 12 are in the centers of the strokes of the letters, with reflector units 15 around them on all sides. The lamps may either be left uncapped, or covered with tinted caps, which color the direct light from the lamps 12, 45 but not the light reflected from the units 15. For illuminated borders, steady or flashing,—illuminated friezes, etc., lamps and reflectors may also be arranged as in Fig. 7. The units 15 can be used in lighting fixtures of various sorts, and for many other 50 purposes.

I claim:

1. An illuminated display comprising a light source, and a plurality of shallow reflector units illuminated thereby from in front 55 cooperating to form the display design; the individual unit comprising a series of reflector elements adapted to reflect forward the incident light from said source, and a common light-permeable protective cover in front of said elements.

2. An illuminated display comprising a light source, and a plurality of reflector units illuminated thereby from in front 60 65 cooperating to form the display design; the

individual unit comprising a multiplicity of parallel reflector elements in a plane approximating that of the sign as a whole adapted to reflect forward the incident light from said source.

3. An illuminated display comprising a light source, and a plurality of reflector units illuminated thereby from in front cooperating to form the display design; the individual unit comprising a series of reflector elements extending side by side and adapted to reflect forward light from said source incident obliquely thereto.

4. A reflective display unit comprising a series of reflector elements in a common plane making a common angle therewith and adapted to reflect forward light incident from in front, and a common light-permeable protective cover for said elements.

5. In an illuminated display, the combination of a light source, and reflective illuminating units illuminated thereby from in front 80 cooperating to form a display design; the individual unit comprising a multiplicity of reflector elements extending side by side in a common plane and making such angle therewith as to reflect forward normal to said plane light from the source incident from in front of the unit oblique to said plane.

6. In an illuminated display, the combination of a light source, and reflective illuminating units illuminated thereby from in front 85 cooperating to form a display design; the individual unit comprising a series of reflector elements extending side by side and adapted to reflect forward normally light from the source incident from in front of the unit obliquely of the series.

7. An illuminated display comprising a light source, and a plurality of reflective illuminating units illuminated thereby from in front 90 cooperating to form the display design; the individual unit comprising a shutter-like series of slat-like reflector elements adapted to reflect forward light from the source incident from in front of the unit 100 obliquely to the series.

8. A reflective display unit comprising in one piece of glass a shutter-like series of 105 slat-like reflector elements with sloping faces in front and a securing base or shank at the rear; adapted to reflect forward normal to the series light incident from in front oblique thereto.

9. A reflective display unit comprising in one piece of glass a shutter-like series of slat-like reflector elements with sloping faces in front and a securing base or shank at the rear; together with a flat-surfaced light-permeable cover secured in front of said reflector elements.

In testimony whereof, I have hereunto signed my name.

KATHERINE LIMPERT.
